UNITED STATES PATENT OFFICE.

WILLIAM ARNOLD LEWIS, OF CHICAGO, ILLINOIS, ASSIGNOR TO "HOLLOW AXLE MANUFACTURING COMPANY," OF MISHAWAKA, INDIANA.

IMPROVEMENT IN THE PROCESS OF MAKING HOLLOW METALLIC AXLES.

Specification forming part of Letters Patent No. 124,833, dated March 19, 1872.

Specification describing an Improved Process for the Manufacture of Hollow Metallic Axles, invented by WILLIAM ARNOLD LEWIS, of Chicago, in the State of Illinois.

This invention is especially adapted for the production of hollow axles of large size. The process is as follows: Plates or heavy sheets of wrought-iron or steel are rolled with parallel sides and of proper dimensions to allow of cutting from each of said plates one or more blanks, which may be afterwards bent into the sections of an axle. In the act of rolling the aforesaid plates the proper increase of thickness may be imparted at points where the journals are to be made. The plates having been thus rolled, are next cut into lengths for axles, and then stamped out into proper outline, so that when bent into concavo-convex or segmental form they may be welded together in pairs to make complete axles.

In the accompanying drawing, Figure 1 is a side or edge view of a plate or bar adapted for the production of three lengths of axle-section blanks. Fig. 2 is a top view of the same. Fig. 3 is a front elevation of portions of a pair of rolls adapted for the rolling of a bar, such as shown in Figs. 1 and 2. Fig. 4 is a transverse section of the same at $x x$, Fig. 3. Fig. 5 is a plan on a larger scale of a single length cut for one axle-section blank. Fig. 6 is a side or edge view thereof. Fig. 7 is a plan of a flat blank cut, in readiness for bending into an axle-section. Fig. 8 is an edge view of the same. Fig. 9 is a vertical section of parts of the cutting apparatus employed to produce a flat blank, such as shown in Fig. 7, from a bar, such as shown in Fig. 5. Fig. 10 is a plan of a blank swaged into concavo-convex form preparatory to being welded to another of corresponding form to make a complete hollow axle. Fig. 11 is a transverse section at $y y$, Fig. 10. Fig. 12 is a vertical sectional view of a pair of swaging-dies and their accessories, which may be employed to form the blank shown in Figs. 10 and 11. Fig. 13 is a horizontal section of the same, showing a plan of the lower die. Fig. 14 is a sectional view of a part of the furnace, and of the dies by means of which the axle-sections are welded together in pairs. Fig. 15 is an elevation of a finished axle.

General Description.

A represents a bar, produced of any desired length and width by passing between the rolls B B'. The bar A may be made of uniform width and of unequal thickness, $a a$ a being thick portions where the arms or journals are to be formed. These inequalities in thickness are produced by the varying depth of the groove b in one or both of the rolls, as illustrated in Figs. 3 and 4. The bar shown in Figs. 1 and 2 is adapted for the production of three axle-sections. It is severed at the thickest parts $a a a$, and each of these separate pieces is then cut into a blank of proper shape, as illustrated in Fig. 7. This cutting is performed by a shear or punch, such as shown in Fig. 9, or by other appropriate mechanism. By such means the severing and shaping of the blanks may be performed at one operation, either from bars of single width, as illustrated in Figs. 2 and 5, or from extended sheets, from the width of which a number of blanks may be cut. In Figs. 7 and 8, 1 1 represent the portions which are to form the axle-arms or journals; 2 2, the projecting parts, which are to constitute the collars; 3 3, the extremities, on which are to be cut the screw-threads to receive the nuts; and 4 5, upward enlargements, which impart great strength to the axle, and take the place of the wooden stock used with axles of common form. The recesses to receive the hounds may be formed in the projections 4 4; and that to receive the reach or perch in the central projections 5, either in the first cutting of the blank, or entirely during the final welding and swaging process. The flat blanks thus formed are next bent into half-oval form with flat edges, substantially as shown in Figs. 10 and 11. This may be effected by heating the flat blank in any suitable furnace—such, for example, as that shown in Fig. 13—and then placing them between dies, Fig. 12, which dies being actuated by levers or by a drop instantly impart to the blank the shape shown in Figs. 10 and 11. A pair of such blanks, secured face to face, are then placed within the furnace F, and, without being removed from the heat of the said furnace, are placed between welding and swaging dies D, which are so formed as to impart

the proper contour to the finished axle. Axles of large size are made of elliptical cross section to impart greater vertical strength.

My invention in this case is not a wholly new process of making hollow metallic axles, but is an improvement on the processes heretofore practiced, the improvement being the rolling of the plate to irregular thicknesses; the cutting of the sections from said plate; and the swaging of those sections in dies, all as described and shown; the subsequent operation required to complete the axle being the same

as those described in Letters Patent granted to my assignees, Hollow Axle Manufacturing Company, October 1871.

What I claim, therefore, and desire to secure by Letters Patent, is—

The improved process herein described of manufacturing hollow metallic axles.

WM. A. LEWIS.
